GATE CLOSING AND LOCKING MECHANISM
FOR DISCHARGE OUTLETS OF CAR HOP-
PERSGeorge B. Dorey, Westmont, Quebec, Canada, as-
signor to Enterprise Railway Equipment Com-
pany, Chicago, Ill., a corporation of Illinois

Application April 9, 1949, Serial No. 86,574

10 Claims. (Cl. 105—282)

1 My invention relates to an improved discharge outlet for hoppers such as used in railway hopper cars and the like and my invention especially relates to the means employed for forcing a sliding gate to fully closed position and retaining the same in closed position.

It is an object of my invention to make use of the means employed for retaining the gate in closed position to serve also in combination with the frame structure as a sealing element to complete the enclosure of the projecting end of the sliding gate.

Another object of my invention is to make use of toggle acting mechanism in the operation of a sealing device whereby the principle of multiplied mechanical advantage is obtained in the final stage of the latching operation to force the gate home and to retain it positively in closed position against lengthwise movement.

A still further object of my invention is to provide a latching device which will act simultaneously on the full width of the gate and apply the forcing pressure evenly thereby insuring against canting and binding of the gate against the vertical side walls of the frame.

My invention is of special importance in connection with sliding gates which are adapted to receive auxiliary sealing through the employment of side and end resilient gaskets for cooperation with the side and end walls of the supporting frame. While the sealing effect obtained through the surface contact between the bearing surfaces of the gate and supporting runways is usually sufficient for most commodities, it is frequently desirable with finely comminuted and free flowing commodities to provide auxiliary sealing means. To this end it is now proposed to provide a structure which will function with the general run of commodities without the use of gaskets but which will be adapted to receive gaskets when necessary for special services.

It is therefore another object of my invention to provide sealing and latching means for the outer end of the gate and frame which will be suitable for use with the gate irrespective of whether or not auxiliary gaskets are employed. My invention further resides in the frame and door structure in relation to the locking mechanism and other parts.

For further comprehension of my invention reference may be had to the accompanying drawings wherein:

Fig. 1 is a top plan view of a discharge outlet assembly incorporating my improvements.

2

Fig. 2 is a vertical side elevational view of the assembly shown in Fig. 1.

Fig. 3 is a partial vertical sectional view taken through the side wall of the outlet on a line 3—3 of Fig. 2.

Fig. 4 is a vertical sectional view on an enlarged scale taken through the outer end of the outlet as seen on a line 4—4 of Fig. 1.

Fig. 5 is a side vertical elevational view on an enlarged scale of the outer end of the assembly showing the latching mechanism in released position with the latching shaft in raised position above the gate.

Fig. 6 is a fractional side view of the outer end of the outlet assembly showing the position of the links in right angular relation and indicating the maximum swinging range of the anchored linkage.

Fig. 7 is a sectional view along the line 7—7 of Fig. 1 through the outer end of the frame and showing the position of the latching shaft as it approaches the notches.

Fig. 8 is a plan view of the latching element.

Fig. 9 is an end view of the latching element shown in Fig. 8.

Fig. 10 is a longitudinal sectional view taken through the latching element as seen on line 10—10 of Fig. 9.

Fig. 11 is a top plan view of the inner toggle link.

Fig. 12 is a side view of the inner link shown in Fig. 11.

Fig. 13 is a top plan view of the outer toggle link.

Fig. 14 is a side view of the outer toggle link shown in Fig. 13.

Fig. 15 is a vertical sectional view taken through the upper outer end of the outlet showing the use of a supplementary insulating curtain of flexible material in connection with my improved latching device.

Fig. 16 is a view in front elevation of the supplementary insulating curtain and related parts shown in Fig. 15.

In the drawings A indicates an outlet frame, B a sliding gate, C longitudinally extending runways on which the gate B is slidably mounted, D an operating shaft with a pinion E fixedly mounted thereon, F a shaft bearing and extension members on each side of the frame, G inner toggle links, H outer toggle links, J a latching element assembly with its associated locking bolt K.

The frame A is formed with an upper preferably four-sided hopper portion including out-

wardly sloping side wall 10—10, Figs. 1 and 2, and similarly sloping end walls at the inner and outer ends of the frame as indicated at 11 and 12 respectively. The upper portion is for the purpose of enclosing and uniting with the lower portion of a load containing hopper such as formed by the sloping floors of a railway car to which the outlet is attached.

The frame A, which is preferably formed of a steel casting, is provided with an aperture 13, Fig. 4, adjacent the outer end 12 of the frame for the accommodation of the gate B therethrough. The frame A is extended below the gate B to provide a four-sided chute like portion L including vertical side walls 14—14, an end wall 15 adjacent the inner sloping upper wall 11 and an outer crosswall structure of angle shape including a depending wall 16 and a substantially horizontally disposed wall 17, the upper face 18 of said wall 17 in combination with the under surface 19 of end wall 12 constituting respectively the horizontal lower and upper boundaries of the aperture 13.

Adjacent the lower margin of the chute walls defining the discharge outlet the frame A is provided on the four sides with outwardly laterally projecting means to receive a removable extension chute (not shown) as indicated in Figs. 1 and 2 at 20, 21, 22 and 23 respectively. Said means on two adjacent sides as indicated by members 20 and 21 are in the form of an outstanding flat ledge 24 and 25 respectively and on the other two sides the members 22 and 23 are bent to form grooves as shown at 26 and 27 respectively. Said members 20 and 22 are of angle shape with vertically disposed flanges 28 secured to the side walls 14 and members 21 and 23 are disposed outwardly of the chute end walls 15 and 16 and riveted thereto.

The side supporting runways C on which the gate B is arranged to have sliding movement are formed of angle shaped members including a substantially horizontally disposed flange 29, Fig. 4, and a depending flange 30, the latter lying flatwise along the inner surface 31 of the upright walls 14—14 and riveted thereto as indicated at 32, Fig. 2. The inner end of the frame A intermediate the upper attaching wall 11 and the lower inner wall 15 of the chute is provided with a horizontal ledge 33, Fig. 2, disposed in alignment with the horizontally disposed flange 29 of the respective side runways C and welded thereto at the end as indicated at 34 to provide a continuous three-sided supporting surface for the gate B. The angle shaped side runways C extend from the end supporting ledge 33 beyond the horizontally extending lower wall 17 of the aperture 13. They have their vertical flanges notched at 35, Fig. 4, to straddle the end walls 16 and 17 of the chute L and the operating shaft D. The horizontal flanges 29 are extended uninterruptedly from the ledge 33 beyond the outer end of the gate B when in closed position and terminate adjacent the end of the frame side walls 14.

The gate is prevented from upward movement by the under surface 19 of upper end wall 12 and by laterally extending lugs 36 which are formed integrally with the frame A. The inner surfaces 31 of the side walls 14—14 operate as guides to engage the side edge portions 37 of the gate B.

The sliding gate B is a plate having a substantially flat upper face 38 and beveled sides 39 and a beveled end 40. The gate B when in closed position, is adapted to rest on the flanges 29 of the runways C and end ledge 33 and adjacent its

side and end edges it is provided with depending end and side walls indicated at 41 and 42, Figs. 1 and 3. Attached to these end and side walls 41 and 42 are resilient gaskets of tubular form as shown at 43 and 44. The side walls 42 and associated gaskets 44 are disposed in slightly divergent relation to provide a wedge shaped formation adapted to register with a similarly wedge shaped formation on the frame A as provided by the edge portions 45, Fig. 3, of the adjacent flanges 29 of the runways C. It will be understood that these edge portions 45 of the respective runways are disposed in slightly divergent relation to provide a wedge shaped interior formation corresponding to the wedge shaped formation on the gate B as set forth in more detail in copending application Serial No. 67,215, filed December 24, 1948, and assigned to the assignee of this application.

The underside of the gate B is formed with rack teeth 46 and co-operable therewith for moving the gate is the toothed pinion E on the shaft D. Each alternate tooth 46 is extended transversely to each side of the gate to unite integrally with the depending side walls 42. The shaft D is pivotally mounted in trunnion like bearings 47, Fig. 5, formed integrally with the bearing members F which are riveted as indicated at 48 to the side walls 14 of the frame. The side walls 14 are indented at 49 in order to straddle the shaft D. The bearing members F extend beyond the walls 14 and are provided with forwardly projecting extensions 50 which extend beyond the frame A and secured to them are rail members 51 for supporting the gate B in opened position.

The gate B is maintained in fully closed position by means of the bodily movable latching element J, Figs. 1, 8 and 10, which extends entirely across its front end. The latching element J preferably includes a body portion or tube 52 formed of a hollow tubular member in the form of length of commercial pipe and fixedly attached thereto at the ends are arms 53 and 54 the latter being provided with a bell crank handle portion 55 and a key shaped aperture 56 for receiving locking bolt K. The arms 53 and 54 are provided with laterally extending sections which extend within the tube 52 and are welded thereto, the projection in the case of arm 53 consisting of a circular shaped portion 53' lying in the tube 52 and in the case of arm 54 the projection is of extended length and crescent shape as indicated at 57 to provide a bearing 58 in which the locking bolt K is mounted for lengthwise and limited rotary motion. The pipe 52 is formed with cut-away segmental shaped portions 59 and 60 to allow for welding at as 61 and 62 and also to provide sufficient clearance to permit the desired turning motion of the locking bolt K in connection with the arm 54.

The arms 53 and 54 are disposed outwardly of the side walls 14 and pivotally united therewith are the inner and outer toggle links G and H. These links are pivotally united at one end with the arms 53 and 54 as at 63, Fig. 6, and with the frame A at 64. The respective links are preferably formed with integral apertured leg portions 65, Figs. 11, 12, 13, and 14, through which rivets 66 extend. In order to provide a secure anchorage for the links G and H relatively to the frame A, integrally formed upright arms 67, Fig. 5, lead upwardly from the outer ends of the trunnion like bearing portions 47, said arms 67 of the hubs being disposed in alignment with the corresponding arms 53 and 54 of the latching element J.

5

The respective aligned arms 53 of the frame A and arms 53 and 54 of the latching element J are then sandwiched between the two parts of the link assembly formed by links G and H.

The inner links G lie in the planes of the ends of latch body portion 52 and are of saddle shape to provide an indented portion 68 to accommodate it between the pivotal axes 63 and 64 of the linkage. The outer links H lie outwardly of the ends of the latch body 52 and include a plate body portion 69 having a key shaped aperture 70 adapted to register with the aperture 56 in the arm 54, when the latch body 52 is in latching position with its longitudinal axis lying slightly to one side of a line joining the pivotal axis 63 and 64.

At the ends of the respective walls 14 there are formed notches 71, Fig. 6, having an interior contour of substantially semicircular shape conforming to the shape of the exterior contour of the latch body 52 for receiving the same to hold it against upward displacement. The lower face of each notch 71 aligns with the bearing face of the runway C and the upper bearing face thereof leads outwardly and upwardly tangentially from the circular face as indicated at 12 in order to provide a flared approach to the pocket. The latching element J is adapted to assume a latching position in the notches 71 in the path of movement of the gate B and is movable therefrom by a movement of rotation to a released position above the path of movement of the gate B. The latching element J is in its transition from one position to another moves along upwardly inclined runways 73 which are the edge portions of upwardly disposed extensions 74 formed integrally with members F. The latching element J is maintained in released or unlatched position by knuckling to its position as indicated in Fig. 5. A stop 75 is provided on each of the arms 53 and 54 which engages with the upper edge 76 of the outer links H, the stop 75 on arm 54 actually being an offset in the lever 55 to dispose the latter outwardly of the frame A sufficiently far to provide clearance for manually grasping it.

The latching element J in its movement between its extreme positions is compelled to follow closely the inclined runway 73 by reason of the fact that the upward throw of the linkage is limited by contact between the upper surface 17, Fig. 6, of the humped portion of link G, and the under surface 18 of wall 12. With the limitation placed upon the upward movement of the linkage, it will be observed that the latching element J is then confined to a circular path as indicated at 78a along which it can move to fully opened knuckled position, Fig. 5, or move toward closing position by entering within the plane of the beveled portion 72 and having its further movement controlled thereby. The body of the latching element J in its movement to closed position sweeps along the outer face of the gate B which is formed with ribs 79 and a slightly receding inclined face 80 to counteract any lifting tendency of the gate B due to the sweeping action of the latch.

The latching element J in latching relation rests on the runways C and is positioned in the path of movement of the gate B and lies in the notches 71, being there retained against upward displacement and also maintained against longitudinal movement by reason of having its axis in dead center locking relation with respect to the axial pivots 63 and 64 of the linkage as-

6

sembly G and H. The circular body portion 52 bears against a continuously extending horizontal wall 81, Fig. 4, on the gate B which has an inclined face 82 forming a downward continuation of the inclined faces 80 of the ribs 79.

Extending from the upper and of the end wall 12 there is a sloping wall 83 which extends between the side walls 14—14 downwardly and forwardly to overlie the projecting portion of the gate B. The under surface 84 of the lower margin of the wall 83 is disposed tangentially to the circular contour of the latch element J, the surface 84 extending upwardly in alignment with the upper beveled surfaces 72 of the notches. The lower margin of wall 83 is of bulb formation 85 thereby providing a rugged lip for contacting with the latching element J.

My improved construction is further adapted to receive a flexible sealing curtain 86 as shown in Figs. 15 and 16 and to this end laterally extending wings 86', Fig. 1, forming a continuation of wall 83 are provided. The said wings are provided with bolt holes 87 for securing a furring 88 for holding the sealing curtain 86 which may be tar paper, canvas, rubber, or similar flexible product. The sealing curtain 86 is long enough to extend over the wall 83 and the wings 86' and wide enough to cover the wall 83 and extend around the body portion 52 of the latching element J in the latched position shown in Figure 15. The furring 88, extending along the upper edge of the wall 83 and secured thereby to bolts extending through the holes 87 therein, serves to clamp the upper edge of the curtain 86 in position. The remainder of the curtain 86 is free to be wrapped around the body portion 52 of the latching element to prevent egress of finely divided lading, such as cement, therewith.

With the mechanism in toggle locked position, the projecting end of the gate B is completely enclosed within the housing formed by the walls 14—14 and the cope shaped member formed by walls 12 and 83.

The positioning of the body portion 52 of the latching element J in the notches 71 and in bearing contact with the gate B and runways C and with the face 84 of the wall 83 assures complete enclosure and sealing of the end of the gate B. This sealing is further enhanced by the interposition of a sealing curtain 86 between the latching element J and the respective bearing surfaces on the gate B and frame A.

The locking bolt K is generally formed of a circular shaped bar 89, Fig. 10, having at one end an enlarged circularly shaped lug 90 and at the opposite end a key shaped projection 91 formed with a seal receiving aperture 92. Intermediate the ends thereof a handle 93 is provided. The locking bolt K seats in bearing 58 of the arm 54 and is maintained in axial relation with respect to the latching element J by means of the bearing lug 90 which also acts as a stop to limit outward sliding movement of the latching element J. When the latching element J is moved to the position shown in Figures 1, 2 and 4, the key shaped projection 91 of the locking bolt K registers with the key shaped aperture 70 in the adjacent outer link H. Thereupon the locking bolt K is moved axially outwardly of the latching element J through the aperture 70 where the usual seal can be inserted in the aperture 92 therefor.

I claim as my invention:

1. In a discharge outlet assembly including a

frame having a discharge opening and a gate slidably mounted therein for closing the opening, latching means for retaining said gate in closed position including a bodily movable latching element extending along the full width of said gate and adapted to assume a latching position in the path of movement of one side thereof and movable by rotation to assume a position above the path of movement of and out of contact engagement with said gate, and locking means cooperating with said latching element to hold the same against rotation in the latching position.

2. In a discharge outlet assembly including a frame having a discharge opening and a gate slidably mounted therein for closing the opening, at least one wall of said frame to one side of said gate having a notch aligned with the end of said gate in closed position which end is movable away from said frame to open position and opening generally in the direction of opening movement of said gate, latching means for said gate including a latching element bodily movable by rotation thereof to a position in the path of movement of said end of said gate and having a portion adapted to interfit with said notch when said element is moved to latched position so as to extend through said notched wall, and means for moving said latching element by rotation thereof including an arm projecting radially from said portion thereof beyond said notched wall and link means pivoted at one end to said arm and at the other end to said wall whereby said latching element can be swung to latched position with said portion in said notch and between the pivotal connections to said link means.

3. In a discharge outlet assembly including a frame having a discharge opening and a gate slidably mounted therein for closing the opening, the walls of said frame at the sides of said gate having notches aligned with the end of said gate in closed position which end is movable away from said frame to open position and opening generally in the direction of opening movement of said gate, latching means for said gate including a latching element extending along the full width of said gate and bodily movable by rotation thereof to a position in the path of said end of said gate and having end portions adapted to interfit with said notches respectively when said element is moved to latched position so as to project beyond said notched walls, and means for moving said latching element by rotation thereof including aligned arms projecting radially from said end portions of said latching element beyond said notched walls and link means pivoted at one end to each of said arms and at the other end to the respective wall of said frame whereby said latching element can be swung to latched position with said end portions in said notches and between the pivotal connections to the respective link means.

4. In a discharge outlet assembly including a frame having a discharge opening and a gate slidably mounted therein for closing the opening, the walls of said frame at the sides of said gate having notches aligned with the end of said gate in close position which end is movable away from said frame to open position and opening generally in the direction of opening movement of said gate, latching means for said gate including a tubular latching element extending along the full width of said gate and bodily movable by rotation thereof to a position in the path of said end of said gate and having end portions adapted to interfit with said notches respectively

when said element is moved to latched position so as to project beyond said notched walls, means for moving said latching element by rotation thereof including aligned arms projecting radially from said end portions of said latching element beyond said notched walls and link means pivoted at one end to each of said arms and at the other end to the respective wall of said frame whereby said latching element can be swung to latched position with said end portions in said notches and between the pivotal connections to the respective link means, and means for preventing displacement of said latching means from its latching position including a locking bolt mounted for axial movement within one end of said tubular latching element to project beyond the same, the associated link means having an aperture aligned with said locking bolt for receiving the same only when said tubular latching element occupies the latched position to hold the same thereat.

5. In a discharge outlet assembly including a multisided frame having a discharge opening and a sliding gate for closing the opening, said frame having upright side walls disposed at each side of said gate and extending lengthwise in the general direction of movement thereof and runways extending laterally inwardly from said walls to underlie and support said gate, a tubular latching element extending along the full width of said gate and bodily movable by rotation thereof to a position in the path of the end of said gate which end is movable away from said frame to open position with the ends of said latching element movable along said runways and extending beyond said side walls, means for moving said latching element by rotation thereof including aligned arms projecting radially from its ends and link means pivoted at one end to each of said arms and at the other end to the respective side wall and arranged to fold to a dead center latching position with respect to said arms and said tubular latching element with the latter in the path of said end of said gate and to open to a knuckled opened position upon movement to release, and means for directing the movement of said tubular latching element along a predetermined path from the locking to unlocking position including inclined supporting rails carried by said runways and leading upwardly from said runways and arranged and adapted to have said ends of said tubular latching element slide therealong.

6. In a discharge outlet assembly including a multisided frame having a discharge opening and a sliding gate for closing the opening, said frame having an aperture in one of the sides for the passage of the gate therethrough, said gate when in closed position projecting beyond said aperture, upright walls at each side of said projecting portion of said gate and runways extending laterally inwardly from said walls to underlie and support said gate, said walls having generally semicircular notches with the innermost portions aligned with the projecting end surface of said gate when the same is closed and opening generally in the direction of opening movement of said gate, a tubular latching element extending along the full width of said gate and bodily movable to a position juxtaposed to said end surface of said gate with the ends thereof movable along said runways and extending beyond said side walls and arranged to interfit with said notches whereby said tubular latching element is held against upward movement, and operating means connected to said ends of said tubular latching ele-

ment for shifting the same from latching position against said end surface of said gate to a position out of the path of movement of said gate.

7. In a discharge outlet assembly including a frame having a discharge opening and a sliding gate for closing the opening, side walls disposed at the sides of said opening, means for moving said gate including interengaging rack and pinion means on said gate and frame respectively and an operating shaft for said pinion, bearings for rotatably supporting said shaft carried by said side walls and including laterally projecting hub portions, said side walls having notches aligned with the end of said gate in closed position which end is movable away from said frame to open position and opening generally in the direction of opening movement of said gate, support arms spaced outwardly from said side walls and leading upwardly from the outer ends of said bearing hubs, latching means for said gate including a latching element extending along the full width of said gate and having end portions adapted to interfit with said notches respectively when said element is moved to latched position so as to project beyond said notched walls, and means for moving said latching element from latched position against said end of said gate and in said notches to a position above said gate and out of the path of opening movement thereof including aligned arms projecting radially from said end portions of said latching element beyond and spaced outwardly from said notched walls in coplanar relation to said support arms, and plate-like links disposed on opposite sides of each set of support and radially extending arms and pivotally connected thereto whereby said latching element can be swung to latched position with said end portions in said notches and between the pivotal connections to the respective links and to unlatched position above said gate.

8. In a discharge outlet assembly including a multisided frame having a discharge opening and a sliding gate for closing the opening, said frame having an aperture in one of the sides for the passage of the gate therethrough, said gate when in closed position projecting beyond said aperture, upright walls at each side of said projecting portion of said gate and runways extending laterally inwardly from said walls to underlie and support said gate, said walls having generally semicircular notches with the innermost portions aligned with the projecting end surface of said gate when the same is closed and opening generally in the direction of opening movement of said gate, a tubular latching element extending along the full width of said gate and bodily movable to a position juxtaposed to said end surface of said gate with the ends thereof movable along said runways and extending beyond said side walls whereby said tubular latching element is held against upward movement, operating means connected to said ends of said tubular latching element for shifting the same from latching position against said end surface of said gate to a position out of the path of movement of said gate.

9. In an outlet assembly including a frame having a discharge opening and a sliding gate for closing the opening, a tubular latching element extending along the end of said gate in closed position which is movable away from said frame to open position with the ends projecting beyond the respective sides of said frame, aligned arms projecting radially from the ends of said tubular latching element, linkage for each arm pivotally

connected thereto and to said frame with the pivotal connection to each arm spaced from the longitudinal axis of said tubular latching element, each linkage including double links with the inner link overlying the respective end of said latching element and saddle shaped to straddle the same to permit it to assume a dead center position with respect to the pivotal axes of the linkage when said tubular element is in latching position, the outer link of each linkage being disposed outwardly of the respective end of said tubular element and one of said links having an aperture therein in alignment with the opening through said tubular element when it occupies the latched position, and a locking bolt slidably mounted in said tubular member and arranged to interfit with said aperture to lock the apertured link and thereby said tubular element in the latched position.

20 10. In a discharge outlet assembly including a multisided frame having a discharge opening and a sliding gate for closing the opening, said frame having an aperture in one of the sides for the passage of the gate therethrough, said gate when in closed position projecting beyond said aperture, upright walls at each side of said projecting portion of said gate and runways extending laterally inwardly from said walls to underlie and support said gate, said walls having generally semicircular notches with the innermost portions aligned with the projecting end surface of said gate when the same is closed and opening generally in the direction of opening movement of said gate, a tubular latching element extending along the full width of said gate and bodily movable to a position juxtaposed to said end surface of said gate with the ends thereof movable along said runways and extending beyond said side walls and arranged to interfit with said notches whereby 30 said tubular latching element is held against upward movement, operating means connected to said ends of said tubular latching element for shifting the same from latching position against said end surface of said gate to a position out of the path of movement of said gate, wall means 35 on said frame extending between said respective upright side walls above said projecting portion of said gate with the under surface of the marginal edge of said wall means forming a continuation of the upper end surfaces of said notches whereby uninterrupted sealing contact is provided between said frame and said tubular latching element between said side walls, and a sealing curtain secured to and extending substantially the full length of said wall means and downwardly across the adjacent ends of the respective side walls to lie in the path of said tubular latching element so as to be folded around said under surface of said wall means and engage said end surface of said gate and overlie the surfaces of said notches on engagement by said tubular latching element and movement of the same to latching position whereby a tight seal is provided for said aperture in said frame to prevent the escape of fine lading.

GEORGE B. DOREY.
